UNITED STATES PATENT OFFICE.

MADERSON A. CRAWFORD, OF CLIO, LOUISIANA.

INTERNAL-COMBUSTION ENGINE.

1,223,260.

Specification of Letters Patent. Patented Apr. 17, 1917.

Application filed April 17, 1915. Serial No. 22,165.

To all whom it may concern:

Be it known that I, MADERSON ALFRED CRAWFORD, a citizen of the United States, residing at Clio, in the parish of Livingston 5 and State of Louisiana, have invented certain new and useful Improvements in Internal-Combustion Engines; and I do hereby declare the following to be a full, clear, and exact description of the invention, such 10 as will enable others skilled in the art to which it appertains to make and use the same.

This invention relates to engines, and more particularly to engines of the internal combustion type.

The invention has for its primary object to generally improve and simplify the construction of internal combustion engines, and render the same highly efficient in use.

Another object is to provide novel and efficient means for regulating the speed of the engine including means for automatically locking the ignition controlling or timing mechanism in inoperative position.

With these and other objects in view, the invention consists in the novel construction, arrangement and formation of parts as will be hereinafter specifically described, claimed and illustrated in the accompanying drawings, in which:

Figure 1 represents a side elevation of the improved engine.

Fig. 2 represents a top plan view of the engine, illustrating the cylinder in horizontal section.

Fig. 3 represents an enlarged detail sectional view, partly broken away, of the electrical ignition mechanism, and

Fig. 4 represents a detail sectional view 40 on the line 4—4 of Fig. 3.

Referring to the drawing in detail, wherein similar reference numerals designate corresponding parts throughout the several views, the numeral 5 indicates a suitable base upon one end of which is supported the cylinder 6 slidably receiving the reciprocating piston 7 composed of a plurality of plates shaped conformably with the interior of the cylinder and separated by layers of 45 asbestos or other suitable packing 8 designed to render the piston leak-proof. A piston rod 9 is secured to the piston 7, projects outwardly through an aperture formed in the inner head of the cylinder and is connected 50 with a cross head 10 slidably longitudinally between guides 11. One end of a crank

shaft 12 is rotatably supported in a bearing block 13 secured between the free and offset ends 14 of the guides 11, and the shaft is supported adjacent its opposite end in a 60 suitable bearing 15 secured to the base 5. A crank pin 16 is secured eccentrically to a disk 17 carried by one end of the shaft 12 and is connected with the cross head 10 by a rod 18.

The engine is of the double acting type and is formed at its opposite ends or heads with exhaust ports 20 connected with the exhaust pipe 21 and controlled by outwardly closing exhaust valves 22, which are normally retained in closed position by the tension of springs 23 coiled about the stems 24 thereof. The exhaust valves 22 are automatically opened to exhaust the products of combustion from the explosion chambers 75 at the opposite ends of the cylinder 6 by a valve operating mechanism designated generally by the numeral 25 and including a slide bar 26 supported in brackets 27 secured to the base 5 and connected with the 80 cross head 10 by a laterally projecting arm 28 thereof. A pair of spaced arms 29 are adjustably secured upon the slide rod 26 and are adapted to engage the valve stems 24 to automatically open the valves 22 to 85 permit of the exhaust of the products of combustion. The side wall of the cylinder 6 at a point diametrically opposite the exhaust ports 20 is formed with a pair of intake ports connected with a fuel intake pipe 90 30 and controlled by a pair of outwardly closing check valves.

An eccentric 32 is keyed upon the crank shaft 12 intermediate the bearings 13 and 15 and is connected with a slide rod 33 supported in brackets 34 carried by the base 5 by a connecting rod 35 and ring 36 secured to one end thereof and inclosing the eccentric 32, whereby the guide rod 33 is reciprocated during the rotary motion of the crank shaft. A second slide rod 37 is supported above the base plate 5 and in alignment with the rod 33 in brackets 38 and is normally retained in engagement with the rod 33 by the tension of a spring 39.

A pair of spaced spring contacts 40 are secured to the base 5 laterally of the slide rod 37 and are connected with one of the electrodes of spark plugs 41 secured in the opposite ends or heads of the cylinder 6. 110 A pair of contact pins 43 are secured in spaced relation to the slide rod 37 and are

- adapted to engage the spring contacts 40 during reciprocation of the rod to close the circuits between one side of the batteries or other source of electro-motive force 44 and one electrode of the spark plugs 41 through the conductor 45, pin 43, spring contact 40 and conductor 42. The opposite poles of the batteries 44 are grounded in the cylinder 6 by conductors 46.
- 5 10 A centrifugal governor designated generally by the numeral 48 is operably connected with the crank shaft 12 through a belt 49 and bevel gear wheels 50. The governor includes a rotatable frame 51, in which are pivoted a pair of depending arms 52, carrying weights 53 at their lower extremities, adapted to be swung outwardly by centrifugal force during the operation of the engine. The arms 52 are provided with 15 angular extensions 54 engaging the upper extremity of a vertically slidable rod 55 slidably mounted upon a frame 58 secured to the base 5. The rod 55 is normally retained in elevated position by the tension 20 of a spring 57 secured at one end to the frame 58 and at the opposite end to a pivoted latch member 59 upon which the rod 55 is supported. The latch member 59 is normally retained in spaced relation above the 25 slide rod 37 by the spring 57, and is adapted, when the engine exceeds a predetermined speed to be depressed by the vertically movable rod 55, which latter is controlled by the governor 48 so as to engage said latch member 30 in a notch 60 formed in the slide rod 37 and thus lock the latter in inoperative position, as illustrated in Fig. 3. In this position, it is evident that one of the contact pins 43 is retained in engagement with its 35 respective spring contact 40 and the other contact pin 43 is retained in spaced relation to its coöperating spring contact 40, thus retaining the electrical circuit to one of the spark plugs 41 closed and opening the circuit to the other spark plug and causing 40 the engine to cease operation. As the speed of the engine decreases the weighted arms 52 drop and thus permit the vertically slid-
- able rod 55 and latch member 59 to move upwardly under the influence of the spring 57 so as to release the slide rod 37 and permit the engine to continue its operation.
- 55 What I claim is:
1. In an internal combustion engine, a pair of spring contacts, a base supporting said contacts, a slide rod, a pair of spaced contact pins carried by said rod adapted to alternately engage said spring contacts, a crank shaft, driving connections between said crank shaft and said rod, a centrifugal 60 governor connected with said crank shaft, a pivoted latch member movable against the slide rod for locking the latter in inoperative position, and a vertically movable rod operable by said governor for automatically 65 actuating the latch to lock the slide rod against operation.
2. In an internal combustion engine, a supporting base, a pair of spring contacts supported upon said base, a slide rod, a pair 70 of spaced contact pins carried by said slide rod adapted to alternately engage the spring contacts, a second slide rod supported upon said base and engaged with the first-mentioned slide rod, a crank shaft supported 75 upon the base, means connecting the crank shaft with the second-mentioned slide rod, brackets supporting the slide rods, a frame supported upon said base, a pivoted latch member supported by the frame and movable against the first-mentioned slide rod to lock the latter in inoperative position, means normally retaining the latch member in inoperative position, a centrifugal governor, means connecting said governor with said 80 crank shaft, and a depressible rod associated with the governor and movable against the latch member to move the latter to operative position.
- 85 In testimony whereof I affix my signature 90 in presence of two witnesses.

MADERSON A. CRAWFORD.
